UNITED STATES PATENT OFFICE.

MICHAEL E. FITZPATRICK AND JAMES JARDINE, OF BRIDGEPORT,
CONNECTICUT.

GLOVE OR SHOE FASTENER.

SPECIFICATION forming part of Letters Patent No. 371,749, dated October 13, 1887.

Application filed March 3, 1887. Serial No. 229,503. (No model.)

To all whom it may concern:

Be it known that we, MICHAEL E. FITZ-PATRICK and JAMES JARDINE, citizens of the United States, residing at Bridgeport, in the county of Fairfield and State of Connecticut, have invented certain new and useful Improvements in Glove or Shoe Fasteners; and we do hereby declare the following to be a full, clear, and exact description of the invention, so such as will enable others skilled in the art to which it appertains to make and use the same.

Our invention is applicable to the various uses for which clasps are required, but relates more especially to the class of clasps used upon gloves, shoes, arctics, &c., and has for its object to produce a spring-clasp which shall consist of few parts, all of metal, maybe easily and cheaply made, durable in use, and not affected by changes of temperature or by water, which are the most serious objections to the various elastic clasps now in use.

We do not claim, broadly, the use of coiled metallic springs to give flexibility and capacity for yielding to fasteners of this general character; but in our invention one of the engaging parts—*i. e.*, the hook or the eye—is carried by a hollow shell, which is movable relative to the part of the glove or other article to which it is attached. This enables the two parts to be connected, even when they cannot be made to approach each other closely, as is often the case in gloves, with the greatest readiness, for the shell is particularly well adapted to be seized by the fingers and moved against the tension of the spring to such position that the two engaging parts may be united. This could with difficulty be done if the shell were stationary upon the article and it were necessary to seize the small end of the hook or eye projecting from the shell and draw it from the shell and against the tension of the spring to the desired position. In the construction shown the hook is carried by the shell and the eye or catch by the other part of the article to be fastened; but this may be reversed without departing from our invention.

The second part of our invention relates to a retaining-spring which operates to hold the two engaging parts together against accidental displacement.

In order to accomplish these results and produce an elastic clasp that may be readily and quickly engaged and disengaged; but at the same time is not liable to become disengaged in use; we have devised the simple and novel construction of which the following description, in connection with the accompanying drawings, is a specification, numbers being used to indicate the several parts.

Figure 1 is an elevation illustrating our invention in use; Fig. 2, a longitudinal section of the same upon an enlarged scale; and Fig. 3 is a partial section illustrating slight changes in the details of construction, which may be made, if preferred.

1 and 2 denote the two sides or parts of a glove or other garment upon which the clasp is used. The clasp itself consists, as is usual, of two members, one of which we will term, for convenience, the "hook" portion and the other the "catch" portion. The hook portion consists, essentially, of a shank, 3, having at one end a head, 4, and at the other end a plate, 5, which is adapted to be secured to the glove or other garment by means of an eyelet, 6, or in any suitable manner.

7 denotes a shell or case, preferably made round, or nearly so, which is adapted to receive the head and a coiled spring, 8, surrounding the shank, one end of which bears against the head and the other against one end of the shell. At the forward end of the shell, and preferably made integral therewith, is a hook, 9, which is made of suitable shape to engage the catch portion, the exact shape, of course, not being of the essence of our invention. The forward end of the case is closed about the base of the hook, as clearly shown in Fig. 2, leaving a neatly-rounded end to the shell. The other end, likewise, is closed about the shank, which, however, is allowed to slide freely through opening 10 at that end of the case. The catch portion consists of a plate, 11, which is adapted to be secured to the opposite side of the glove or other garment by an eyelet, 12, or in any suitable manner. The inner end of this plate is preferably raised—that is, struck up—as shown in Fig. 2, and is provided with an opening, 13, to receive the hook, the opening of course being just large enough to re-

ceive the hook and being smaller than the raised portion, so that the hook will catch under the flange 14 of the raised portion.

In order to insure that the hook shall not be disengaged in use, we provide a spring, 15, within the raised part of the catch portion, as clearly shown in Figs. 2 and 3. This spring is of course made of suitable shape to correspond with the shape of the hook and flange, as shown in Figs. 2 and 3, so that when the hook is engaged with the flange it is held closely in position and cannot become disengaged except by backward and downward pressure against the spring. The spring may be secured in place in any suitable manner; but we preferably make it extend under the plate and secure it in place by eyelet 12, as clearly shown.

The operation is so simple as hardly to require explanation. It will be seen that when the shell or case is pushed forward spring 8 will yield. The instant, however, that the case is released the spring throws it back to its normal position. To engage the parts of the fastener it is simply necessary to draw the two parts 1 and 2 together and place the hook in opening 13. Spring 8 will instantly act to draw the shell and hook backward, and spring 15 will act to hold the hook against the flange of the catch portion. To disengage the parts the shell is simply pushed forward against the power of spring 8, which forces the hook backward against the power of spring 15. It may then be lifted out, and the parts will resume their normal position.

It will of course be understood that the details of construction may be varied within reasonable limits without departing from the spirit of our invention.

40 We claim—

1. In a fastener, the combination, with the

catch portion, of a hollow shell having a hook at its forward end carried by said shell in its movement, a spring within the shell, a shank connected with and adapted to compress the spring and projecting through the rear end of the shell, and means, substantially as described, whereby the shank may be attached in fixed position, leaving the shell movable to carry the hook, substantially as set forth. 45

2. In a fastener, the combination, with the spring-controlled hook, of the catch portion provided with the spring 15, whereby the hook is held in engagement with the catch portion, substantially as set forth. 50

3. The combination, with a shell, hook, shank, head, and spring 8, of plate 11, having opening 13, flange 14, and spring 15, whereby the hook is held in engagement with the flange. 55

4. In a glove or shoe fastener, catch-plate 11, having an opening, 13, and flange 14, in combination with a hook adapted to engage said flange, a spring, 15, adapted to hold said flange and hook in engagement, and means— 60 for example, an eyelet—whereby the plate and spring are secured to the glove or other article and retained in operative position. 65

5. In a fastener for gloves, shoes, &c., the combination, with a suitable catch-plate, of a hook and shell made in a single piece, a shank having a head within said shell and adapted to slide through its end, and a spring bearing against the end of the shell and the head. 70

In testimony whereof we affix our signatures 75 in presence of two witnesses.

MICHAEL E. FITZPATRICK.
JAMES JARDINE.
